CARL MÜNZE, OF SPANDAU-EISWERDER, GERMANY, ASSIGNEE, BY MESNE ASSIGNMENTS, TO KEYES CONTAINER CORPORATION, OF BOSTON, MASSACHUSETTS, A CORPORATION OF MAINE

APPARATUS FOR THE MANUFACTURE OF HOLLOW BODIES FROM FIBER PULP

Application filed November 28, 1928, Serial No. 322,452, and in Germany September 7, 1928.

This invention relates to improved apparatus for manufacturing hollow bodies from fiber pulp.

Processes are known according to which the pulp is moulded into hollow bodies, such as packing boxes, in hinged moulds with permeable walls by means of a gaseous fluid under pressure (steam, compressed air, and the like.) Machines, apparatus and devices are also known for automatically supplying the fiber pulp and one or more gaseous fluids under pressure to such moulds and for controlling the opening and closing of the latter.

The object of the invention is to provide improved apparatus of the character referred to, and the invention mainly consists in combining a plurality of the said moulds into a single compound mould and in supplying thereto the fiber pulp, compressed air, etc. from a single machine over a distribution point in such a manner that the opening, the closing and the actual moulding process is effected simultaneously in all the individual moulds of the compound mould, and that the individual moulds deliver the finished moulded articles also simultaneously.

The invention is of great economical importance. The output of the apparatus is increased in proportion to the number (2, 3 or more) of moulded articles simultaneously delivered by the compound mould, so that wages and overhead expenses and the allowances for depreciation are considerably reduced. Substantial advantages are also obtained from a thermal point of view, since the unavoidable heat losses are distributed over a larger number of finished articles. Further, there is also a saving in power, compressed air, steam, etc., since the power generated and the gaseous fluid under pressure depend upon the quantity of heat required.

As a rule the improved apparatus will be used for the simultaneous manufacture of hollow bodies of the same kind or the same weight; it is, however, to be understood that hollow bodies of different kinds or weights may be produced together, for instance two receptacles and their two respective lids.

Experience has further shown that in order to obtain perfect hollow bodies, it is necessary

that the passages through which the fiber pulp is supplied between the common distribution point and the individual moulds shall have the proper cross section, length and curvature according to the quantities of fiber pulp required for the different hollow bodies, otherwise the thickness of the hollow bodies which are obtained will not be uniform since the distribution of the pulp thereto from the common distribution chamber is not uniform.

Referring to the accompanying drawings, which illustrates the invention, by way of example,

Figures 1, 2 and 3 show a form of construction by means of which two receptacles and the two corresponding lids are produced simultaneously,

Figure 1 being a sectional elevation through the improved apparatus,

Figure 2 a transverse section along the line A—B in Figure 1, and

Figure 3 a cross-section along the line C—D in Figure 1.

Figures 4, 5 and 6 illustrate a modified arrangement of a portion of the apparatus,

Figure 4 being a sectional elevation showing the distribution chamber and the moulds,

Figure 5 being a plan view of the bottom part, and

Figure 6 being a perspective view of the distribution chamber with the hollow bodies attached thereto.

Referring to the construction illustrated in Figures 1 to 3, the fiber pulp is admitted into the pipe *a* from the machine (not shown) and flows into a distribution chamber *b* and hence through pipes *c*, *d*, *e* and *f* into the respective moulds *g*, *h*, *i* and *k*, the two outer ones of which, viz. *g* and *k* are used for the production of receptacles and the two inner ones, viz. *h* and *i*, for the production of the corresponding lids. The four moulds *g*, *h*, *i* and *k* are so constructed and united that they can be opened simultaneously by turning around a hinge. In this example of construction, the permeable side walls are secured to the two jaws *l* and *m* which can be turned around the pivots *n* and *o* respectively to open the molds when the hollow bodies are

formed. The bottoms *p*, *q*, *r* and *s* of the four individual moulds are secured to the bottom jaw *t*, which is capable of effecting an opening movement at the proper moment by turning around the pivot *u*.

5 The passages *c*, *d*, *e* and *f* have such a cross-section, length and curvature that they will ensure that the walls of the hollow bodies will be of uniform thickness.

10 As in the present example the inner moulds *h* and *i* require a smaller amount of pulp than the outer moulds *g* and *k*, the passages *d* and *e* have a smaller cross-section than the passages *c* and *f*. Instead of reducing the cross-section of the passages, other means 15 may be employed for preventing a superfluous amount of pulp from reaching the smaller moulds *h* and *i*. Thus, for instance, the lengths of the passages *d* and *e* may be increased by the insertion of bends or the 20 internal resistances of these passages may be altered by the provision of constrictions thereon, which constrictions may be made adjustable if desired.

25 The lengths of the passages between the distribution chamber and the moulds may be varied according to the shape that it is desired to impart to the hollow bodies. In the case of small hollow bodies to be produced 30 simultaneously in a large number, the individual moulds used therefor may be placed very close or immediately next to the distribution point, in which case a symmetrical arrangement is preferably employed. Such 35 a form of construction is illustrated in Figures 4 to 6, in which *v* is the common distribution chamber and *w* are the individual moulds which are combined together into a single unit capable of being swung open 40 along the plane E—F in Figure 4, the bottom part *x* of the mould moving downwards.

In order to facilitate the removal of the 45 numerous hollow bodies from the compound mould according to a further feature of the invention, a portion of the distribution chamber *v* is also made with permeable walls so that a body is obtained such as shown in Figure 6, from which the individual hollow bodies *y* are then removed.

50 I wish it to be understood that the details for carrying the invention into effect may be modified in various respects without in any way departing from the spirit of the invention.

55 What I claim is:—

1. In apparatus for manufacturing hollow bodies from fiber pulp, the combination of a compound mould comprising a plurality of 60 individual moulds having permeable walls, the said compound mould having a unitary outer wall common to all the individual moulds, on which outer wall the permeable walls of all the individual moulds are mounted, with a pulp distribution chamber com- 65

mon to the individual moulds of the compound mould and with means for simultaneously opening the individual moulds.

2. In apparatus for manufacturing hollow bodies from fiber pulp, the combination of a compound mould comprising a plurality of individual moulds having permeable walls, the said compound mould having a unitary outer wall common to all the individual moulds, on which outer wall the permeable walls of all the individual moulds are mounted, with a pulp distribution chamber common to the individual moulds of the compound mould, with pipes connecting the individual moulds to the said distribution chamber and with means for simultaneously opening the individual moulds.

70 3. In apparatus for manufacturing hollow bodies from fiber pulp, the combination of a compound mould comprising a plurality of individual moulds having permeable walls, the said compound mould having a unitary outer wall common to all the individual moulds, on which outer wall the permeable walls of all the individual moulds are mounted, with a pulp distribution chamber common to the individual moulds of the compound mould, with pipes connecting the individual moulds to the said distribution chamber, the cross-section, length and curvature 80 of which are adapted to the quantities of fiber pulp required for the individual hollow bodies and with means for simultaneously opening the individual moulds.

85 4. In apparatus for manufacturing hollow bodies from fiber pulp, a compound mould comprising a plurality of individual moulds having permeable walls, the said compound mould having a unitary outer wall common to all the individual moulds, on which outer wall the permeable walls of all the individual moulds are mounted, in combination with a pulp distribution chamber common to the individual moulds of the compound mould with pipes connecting the individual moulds to the said distribution chamber, the said pipes having substantially equal cross-sections lengths and curvatures and with means for simultaneously opening the individual moulds.

90 5. In apparatus for manufacturing hollow bodies from fiber pulp, a compound mould comprising a plurality of individual moulds having permeable walls, the said compound mould having a unitary outer wall common to all the individual moulds, on which outer wall the permeable walls of all the individual moulds are mounted in combination with a pulp distribution chamber common to the individual moulds of the compound mould and with means for simultaneously opening the individual moulds, the individual moulds being arranged symmetrically with respect to the said distribution chamber so that they are supplied uniformly with the fiber pulp.

6. In apparatus for manufacturing hollow bodies from fiber pulp, a compound mould comprising a plurality of individual moulds having permeable walls, the said compound 5 mould having a unitary outer wall common to all the individual moulds, on which outer wall the permeable walls of all the individual moulds are mounted, in combination with a pulp distribution chamber common to the individual moulds of the compound mould and 10 with means for simultaneously opening the individual moulds, the individual moulds being arranged symmetrically with respect to the said distribution chamber to which they 15 are connected directly, so that they are supplied uniformly with the fiber pulp.

7. In apparatus for manufacturing hollow bodies from fiber pulp, a compound mould comprising a plurality of individual moulds 20 having permeable walls, the said compound mould having a unitary outer wall common to all the individual moulds, on which outer wall the permeable walls of all the individual moulds are mounted, in combination with a 25 pulp distribution chamber common to the individual moulds of the compound mould and having permeable walls and with means for simultaneously opening the individual moulds, the said distribution chamber being 30 connected directly with the individual moulds, whereby a number of moulded hollow bodies is obtained from which the individual hollow bodies can subsequently be detached.

35 In testimony whereof I have signed my name to this specification.

CARL MÜNZE.
